UNITED STATES PATENT OFFICE.

WILLIAM WHARTON, JR., AND EDWARD SAMUEL, OF PHILADELPHIA,
PENNSYLVANIA, ASSIGNORS TO WILLIAM WHARTON, JR., AND COMPANY,
INCORPORATED, OF SAME PLACE.

DESIGN FOR A RAILWAY-RAIL.

SPECIFICATION forming part of Design No. 18,326, dated May 15, 1888.

Application filed April 20, 1888. Serial No. 271,339. Term of patent 14 years.

To all whom it may concern:

Be it known that we, WILLIAM WHARTON, Jr., and EDWARD SAMUEL, both citizens of the United States, and residents of Philadelphia, Pennsylvania, have invented a new and original Design for a Railway-Rail, of which the following is a specification.

Our design for a railway-rail is fully illustrated in the accompanying drawing, the view 10 in which is a transverse section showing the outline of the rail.

The rail has a head, A, projecting laterally from one side of a depending web, B, from the other side of which projects a flange, D, the 15 upper face d of which is in a different horizontal plane from the upper face a of the head A. Depending from the outer edge of the head A is a lip, e, thus forming between the same and the web B a groove, g. A lip, h, depends 20 from the outer edge of the flange D, thus forming between said lip and the web B a groove, i.

We claim—

The herein-described design for a railway-rail having in transverse section the outline illustrated, comprising a depending web, B, a 25 head, A, with lip e depending from its outer edge, a laterally-projecting flange, D, having its upper face in a different horizontal plane from that of the head, and having a lip, h, depending from its outer edge, the said lips e and 30 h forming grooves on opposite sides of the web B, all substantially as shown and described.

In testimony whereof we have signed our names to this specification in the presence of two subscribing witnesses.

WILLIAM WHARTON, JR.
EDWD. SAMUEL.
